INVENTOR

ATTORNEY

UNITED STATES PATENT OFFICE

JOHN A. HANDFORD, OF NEW BEDFORD, MASSACHUSETTS

ELECTRIC SWITCH

Application filed June 13, 1930. Serial No. 460,992.

This invention relates to an electric door knocker and has as its primary object to provide a door knocker embodying an electric switch adapted to be closed when the swinging member of the knocker is actuated, so as to close an electric circuit through a bell or buzzer within the residence upon the door of which the device is mounted, thereby rendering it possible to extend the conductor wires of the bell or other signal system to a bell or buzzer in a servant's room, whereby the servant will be notified when a visitor calls whereas, in the use of the ordinary door knocker, the servant may be so far removed from the door that he would not hear the knocker.

Another object of the invention is to provide an electric signal circuit closing unit which will be installed upon a door and in the body of an ornamental knocker, so that all of the beauty of the knocker will be preserved inasmuch as the actuating element of the circuit closing switch is concealed by the swinging knocker of the device.

Another object of the invention is to provide an electric door knocker by the use of which all of the advantages to be gained by the use of an independent knocker and independent push button for a bell or other signal, may be obtained, in a unitary structure, without the presence of the circuit closing unit being observable.

Another object of the invention is to provide an electric door knocker in which the electric switch will function more effectually than most push button switches, inasmuch as it is contemplated by the invention that it be so constructed as to hold the swinging member of the knocker in a slightly outwardly swung position where it may be conveniently grasped.

This invention also consists in certain other features of construction and in the combination and arrangement of the several parts, to be hereinafter fully described, illustrated in the accompanying drawing, and specifically pointed out in the appended claim, it being understood of course that minor changes may be made so long as they fall within the scope of the claim.

In describing my invention in detail, reference will be had to the accompanying drawing, wherein like characters denote like or corresponding parts throughout the several views, and in which:

Figure 1 is a view in front elevation of the knocker embodying the invention.

Figure 2 is a view in side elevation thereof, the switch unit being shown in elevation and a portion of the body of the knocker being shown in section to better illustrate the said switch unit.

Figure 3 is a detail view partly in section and partly in elevation illustrating the construction of the switch unit and the manner in which the swinging member of the knocker coacts with an element of the switch unit, the view also illustrating, diametrically, the electric signal circuit.

The knocker comprises a body 1 which is of metal and preferably of solid formation except for a recess 2 which is formed in its rear side, this side of the knocker body being flat so that the body may be disposed against the face of a door, indicated by the reference character D and held in place by bolts 3 fitted through openings 4 in the door and having their heads counter-sunk, the inner ends of the bolts being threaded into sockets (not shown) formed in the said flat rear side of the knocker body.

The knocker unit includes the usual swinging knocker member 5 which in the illustrated embodiment of the invention is of arcuate form and the body 2 is formed at the forward end of the recess 2 with an extension 6, the forward end of which is flat as indicated by the numeral 7. The swinging knocker 5 is formed at the intermediate portion of its bow with a head 8 which is somewhat flared in a forward direction so as to provide a finger knob 9, and the body 1 is formed in its portion 6 with an opening 10 which is located directly opposite the head 8 of the swinging knocker.

The rear side of the body 1 is formed with a shallow recess as indicated by the numeral 11, and the numeral 12 indicates a guide member which is of metal and which includes side portions 13 and a connecting end portion

14. The side portions 13, terminate, at their inner ends, in right angularly extending terminal portions 15 which are disposed within the recess 11. Another guide member 16 comprises side members 17 and a connecting end member 18 corresponding to the side members 13 and connecting member 14 of a previously described guide, and the side members 17 are formed with right angular extensions 19 which overlap the extensions 15 of the side members 13 of the first mentioned guide. A cap plate 20, of metal, closes the recess 11, and screws 21 are fitted through openings in this cap plate and through openings in the extensions 11, 15 and 19 of the guide members 12 and 16, and washers 22 of insulating material are arranged upon the bolts 21 between the extensions 19 and the cap plate 20, other insulating washers 23 being arranged upon the bolts and engaging between the heads of the bolts and the cap plate 20.

The openings in the plate 20 are of greater diameter than the bolts 21, so that these bolts 25 are not in contact with the cap plate although they are in contact with the extensions 15 and 19 of the guide members 12 and 16.

A plunger of cylindrical form and of metal, indicated by the numeral 24 is slidably fitted through openings formed in the end members 14 and 18 of the two guide members, and this plunger is likewise slidably fitted through the opening 10 so that one end of the plunger projects beyond the flat 35 end 7 of the said portion 6 of the body of the knocker and therefore is normally in contact with the rear side of the head 8 of the swinging knocker. A collar 25 is fixed upon the bolts 24, and a compression spring 26 is 40 arranged upon the bolt and bears at one end against the collar and at its other end against the connecting piece 18 of the guide member 16, and it will be understood at this point that the spring yieldably holds the plunger 45 24 in a forwardly or outwardly shifted position.

The numeral 27 indicates a small bolt which is fitted through an opening formed in the cap plate 20 at a point in horizontal alignment with the axis of the plunger 24, the head 50 28 of this bolt being rounded and a nut 29 being threaded onto the bolt.

The opening through which the bolt extends is of a greater diameter than that of the bolt, and washers 30 of insulating material are arranged upon the bolt between the head thereof and the cap plate 20 and also between the nut 29 and the said cap plate so that the bolt is concealed from the cap plate.

55 A conductor wire 31 is connected with one of the bolts 21 and to one terminal of a battery 32 or other source of current supply, and a conductor wire 33 is led from the other pole of the battery to one terminal of an 60 electric bell or buzzer 34, which bell or buzzer

will be installed at any desired place within the residence. The numeral 35 indicates a conductor wire which is connected with the bolt 27 and this wire is connected to the other terminal of the bell or buzzer signal 34.

70 From the foregoing description of the invention it will be understood that normally the inner end of the plunger 24 is held, by the spring 26, in spaced relation with respect to the head of the bolt 27 and therefore the circuit will normally be open. However, when the rocking member of the knocker is actuated by a caller or visitor, the impact of the head 8 thereof with the plunger, will result in the plunger being shifted inwardly 75 against the tension of the spring 26 and into engagement, at its inner end, with the head 28 of the bolt 27 thereby closing the circuit, above described. Preferably the distance to which the forward or outer end of the plunger projects beyond the flat end 7 of the extension 6 will be but very slightly greater 80 than the distance between the head 28 of the bolt 27 and the inner end of the plunger, so that the engagement of the plunger with the bolt will be insured, and at this point it will be understood that the swinging knocker may be held, by pressure exerted against it, in such position as to maintain the plunger in such engagement with the bolt 27 if response is not obtained by operating the knocker by several repeated swinging movements as is customary.

85 What I claim is:

90 A device of the kind indicated comprising a body for mounting on a door or wall surface formed with a bore or recess opening on its rear face, a guide disposed in said recess and composed of two members of which each 95 consists of parallel side portions and a connecting end portion, the side portions terminating in oppositely disposed right angular extensions, one of said members being shorter than the other and being disposed between the side portions of the same with its extensions in contact with the extensions 100 of the first, a plunger slidably mounted in guide openings in the end portions of said member, a shoulder on said plunger, a spring surrounding said plunger and bearing one 105 end against the shoulder on the same and the other end against the end portion of the shorter member, a plate spanning the extensions of the two members and having a center contact for engagement by said plunger when depressed, and screws passing through said contact plate and through said extensions to secure said members and the plunger to said body, the latter having an opening in the front wall in axial alignment with said recess 110 to permit the extension of the forward end of the plunger therethrough.

115 120 125 In testimony whereof I affix my signature.

130 JOHN A. HANDFORD.
